UNITED STATES PATENT OFFICE.

JAMES HENSHALL, OF PHILADELPHIA, PENNSYLVANIA.

STEAM-PUMP.

SPECIFICATION forming part of Letters Patent No. 243,776, dated July 5, 1881.

Application filed May 26, 1881. (No model.)

To all whom it may concern:

Be it known that I, JAMES HENSHALL, a citizen of the United States, residing at Philadelphia, in the county of Philadelphia and State 5 of Pennsylvania, have invented certain new and useful Improvements in Steam-Pumps; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 This invention relates to steam-pumps; and it consists in certain improvements in the operating mechanism, as hereinafter shown and described.

In the accompanying drawings, Figure 1 represents a plan of a steam-pump and its operating mechanism with my improvement applied thereto. Fig. 2 represents a side view of certain details detached.

Referring to the drawings, A designates a 25 shaft or spindle, having a piston, B, working in a steam-cylinder at one end, the other end of the spindle carrying a pump-plunger, C, in a tubular chamber, as shown.

30 Adjacent to the steam-cylinder is the chamber D, into which steam is admitted through a pipe, a, the steam passing from thence into the steam-cylinder to actuate the piston, and from thence past the cut-off sliding valve b to the discharge-port c. The course of the steam 35 is shown by the arrows indicated by 1, 2, and 3 respectively.

35 Adjacent to the tube or cylindrical chamber in which moves the pump-piston C is a water-chamber, E, with a sliding cut-off valve, d, located therein, said chamber E communicating with the chamber of pump-piston, as shown, and having a discharge-port, f. The water rises through pipe g, and, passing the slide-valve d to the chamber of piston C, goes from thence 45 into the chamber E and through the discharge f, the course being clearly indicated by the arrows 4, 5, and 6 in the drawings, from which

the operation of the parts above referred to will be readily understood.

The oscillating movements of the slide-valves 50 b and d, respectively, are effected in the following manner: A pivoted rocking-lever, F, is located midway under the spindle A, as shown, said lever at its extremities having suitable connections, h and i, with the slide-valves b and 55 d respectively. To regulate the movements of valves the couplings of h and i to lever F are made adjustable by the slots m in the lever.

A cam, (indicated by G,) which is rigidly fastened to lever F or made solid therewith, extends from said lever at its center and in opposite directions, so as to form two arms, each being somewhat in the form of a lozenge, as shown in the drawings. The cam G has a vertical rim, k, extending entirely around it, within 60 which rim and centrally on each arm of the cam are two raised surfaces, n, which are also somewhat lozenge-shaped, the purpose of this formation being to form a way in the surface of the cam for the movement of a vertical pin, p, carried by the spindle A and extending into the way o formed in the cam. The course of the pin p in the way o is indicated by the dotted line, the pin moving along the way around each 65 of the raised surfaces n, so that in going from 70 one end of the cam to the other its track crosses at the center. To insure the crossing movement of the pin in its passage the way o is made somewhat flaring toward the center of the cam. Thus by the movement of the pin 75 p in the cam G is effected the rocking movement of lever F, and motion is imparted to the valves b and d respectively, the movements of said valves being limited by the cam and adjustable by means of the slots in the extremities of the rocking lever connecting with the valves.

80 In the direct-acting steam-pump a slide-valve is thus actuated by the movement of a cam of peculiar construction, having a movement that renders it impossible to bring 85 the valve to a position to shut off steam and stop the pump. Owing to the peculiar form of the cam from which motion is imparted to the slide-valve a full stroke is insured, and,

further, the pump commences the stroke slowly, giving the water time to fill the water-cylinder, insuring a full supply at every stroke, and preventing the pump-plunger from cushioning against the water when the cylinder is 5 but partly filled.

Having described my invention, I claim—

In a steam-pump, the combination, with the piston-spindle A, carrying a pin, p, the cam 10 G, having the crossing way o and the rocking

lever F, connecting with one or more slide-valves, all arranged substantially as and for the purposes described.

In testimony whereof I sign my name in the presence of two witnesses.

JAMES HENSHALL.
